DESIGN FOR A BELT FOR PERSONAL WEAR

Morris Sachs, Rochester, N. Y., assignor to Hickok Manufacturing Company, Inc., Rochester, N. Y., a corporation of New York

Application February 8, 1934, Serial No. 50,662

Term of patent 3½ years

To all whom it may concern:

Be it known that I, MORRIS SACHS, a citizen of the United States, residing at Rochester, in the county of Monroe and State of New York, have invented a new, original, and ornamental Design for Belts for Personal Wear, of which the following is a specification, reference being had to the accompanying drawing, forming part thereof.

In the drawing:—

Fig. 1 is a perspective view of a belt showing my design, the detailed illustration of the belt body being continued throughout the entire length of the same, the shaded lines denoting contrasting color and there being spaced beadings bordering the central panel of one color running longitudinally throughout the length of the belt body and the outer transverse end of the buckle having transverse ribs aligning with the respective beadings and between said ribs corresponding in color with the color of said longitudinally running panel.

Fig. 2 is an enlarged detail transverse view on the line 2—2 of Fig. 1.

Fig. 3 is an enlarged transverse sectional view on the line 3—3 of Fig. 1.

Fig. 4 is a transverse sectional view on line 4—4 of Fig. 1.

I claim:

The ornamental design for a belt for personal wear, as shown and described.

MORRIS SACHS.
